E. M. BOURNONVILLE,
ROTARY INTERNAL COMBUSTION ENGINE VALVE,
APPLICATION FILED NOV. 28, 1917.

1,293,681.

Patented Feb. 11, 1919.

EUGENE M. BOURNONVILLE, OF JERSEY CITY, NEW JERSEY.

ROTARY INTERNAL-COMBUSTION-ENGINE VALVE.

1,293,681.

Specification of Letters Patent. Patented Feb. 11, 1919.

Application filed November 28, 1917. Serial No. 204,350.

To all whom it may concern:

Be it known that I, EUGENE M. BOURNONVILLE, a citizen of the United States, and a resident of Jersey City, in the county of Hudson and State of New Jersey, have invented certain new and useful Improvements in Rotary Internal-Combustion-Engine Valves, of which the following is a specification.

10 These improvements relate to rotary valves for internal combustion engines, and more especially to the type of rotary combined intake and exhaust valve covered by my Patents 1,118,730 of November 24, 1914, 15 1,119,494 of December 1, 1914, and 1,229,574 of June 12, 1917, and 1,250,548 of December 18, 1917.

In those specifications I have disclosed how a rotary valve exposed to the direct 20 heat of combustion can be effectively cooled by aid of the intake gases passing inside and outside of the rotary valve member, and effectively lubricated by oil carried by these 25 gases and swept along the entire length of the rotating bearing surface, together with various other features, addressed to the general problem of making the rotary valve principle available for this class of engines by overcoming the characteristic and vital 30 defects of seizing, cutting and loss of compression, while avoiding undesirable complications, such as split spring-yielding valve members, packing rings, etc., frequently proposed.

35 One of the present objects is to provide further means for preventing excessive expansion, and particularly excessive local expansion, of the valve member, which is a factor in producing the evils referred to.

40 Other objects are to promote the lubrication, to equalize the temperature and therefore the mass of the charges which pass to the several engine cylinders, and to make possible a reduction in the arc of stationary 45 bearing surface removed at the side containing the longitudinally extending intake opening.

In the accompanying drawings illustrating the invention:

50 Figure 1 is a longitudinal section through a valve member, casing and manifolds taken as indicated by the broken line 1—1 of Fig. 2;

Fig. 2 is a vertical transverse section, showing a portion of one of the engine 55 cylinders; and

Figs. 3, 4 and 5 are fragmentary enlarged views indicating certain specific ways of securing sheet metal pockets to the massive 60 valve member.

Fig. 1 of the drawing corresponds substantially to the form of construction shown in Figs. 1 to 6 of Patent 1,229,574 aforesaid, but it will be understood that I do not limit myself to this form, and that in general 65 any of the features of my several prior specifications may be used in conjunction with the instant improvements, whether herein referred to or not.

The construction to which these improvements are shown applied will be described briefly, the reader being referred to my prior specifications for a completer statement of the features of construction and operation and the functions and advantages 70 involved.

One of the engine cylinders 1 with its slotted head port 4, for both intake and exhaust, is seen in Fig. 2. The valve casing 6 extends lengthwise over the tops of the 80 cylinders, and is formed internally with a bore forming both a valve seat and a bearing surface. At either side of the cylinder ports 4 the casing is provided with intake and exhaust openings, the former comprising 85 a fresh gas manifold 11 formed as part of the cooling system, in the casing casting, and communicating with the bore by a longitudinally continuous or virtually continuous port opening 70, and the latter consisting of 90 exhaust ports 10 leading to a suitable external manifold 33. The casing is water-jacketed, as indicated at 23.

The rotary member is preferably made in two or more cylindrical sections 5, which in 95 the illustrated form are driven through an intermediate skeleton element 60, which in turn is driven by and secured to a centrally extending shaft 54 suitably geared to the engine shaft. The valve member has a central bore or passage 7, and lateral external port pockets 8, the latter to connect the cylinder ports alternately with the intake and exhaust openings at the proper times.

The fresh gases from the carburetor enter 100 centrally of the valve at 67, through the wall

- of the casing into the skeleton driver 60, where the flow divides, the branches thereof passing in opposite directions through the passage 7 to the end chambers 52 and 53, 5 there turning backward through the opposite ends of the manifold 11 and passing to the port pockets 8 serving the several cylinders, as these pockets come into position to connect the ports 4 and 70.
- 10 The first of the improvements of the present invention relates to the manner of forming the port pockets 8, and their relation to the walls of the valve member and to the flow of cooling gas within. Heretofore, I 15 have made these pockets by forming oblong outward-facing recesses in the wall of the rotating member. This construction left a substantial thickness of metal behind or inside the surfaces exposed to the flow of hot 20 gases during the exhaust periods, which resulted in the transmission of a large amount of heat to the valve member and more especially to the regions immediately surrounding the edges or lips of the ports in question, 25 tending to cause undue expansion at high engine speeds. I now propose to make the walls of the port pockets very thin, particularly toward their edges, and to arrange these thin pocket walls so that the fresh 30 gases on the interior can have access to their backs. This is preferably accomplished, as indicated in the drawings, by making openings in the relatively massive wall of the valve member extending through to the central 35 passage at the places where the pockets are to be, and by inserting in these openings dished or trough-like sheet-metal members 82 having the desired form of the pockets. The edges of these sheet-metal pockets are 40 united to the body walls at or near the circumference, and are elsewhere out of contact therewith, leaving recesses 81 behind the pockets permitting access of the cool gases practically to the port lips. Various ways 45 of attaching the sheet-metal to the valve member, by casting, brazing, screwing and riveting, are indicated in the views, but it will be understood that I do not limit myself to any of these, since other modes will 50 suggest themselves to the skilled mechanic. It may be observed that it is not imperative that a fluid-tight joint be made in the first instance between the sheet-metal and body walls, because any slight openings will 55 speedily become closed with carbon in the operation of the engine. By virtue of this construction it will be perceived that there is very little metal located where it can absorb heat from the outflowing exhaust gases when 60 the pockets connect the ports 4 and 10, and that there will be correspondingly little heat transmitted by conduction to adjacent regions, and furthermore that owing to the thinness of the septum between the heat ex- 65 change media, namely the fresh gases on the

inside and the hot gases on the outside, and the presence of the cooling medium practically up to the edges of the port pockets, the cooling of these parts will be particularly efficient.

It will be observed that I make no attempt to utilize light metal for the whole of the valve member and that even the portions which close the cylinder ports during the firing strokes are massive. This is because 7 sheet-metal will not stand the combined effect of the heat and high pressure of the explosion without warping, in addition to which the area exposed to heating through the ports 4 is small as compared with the 8 area of the pockets 8. The sheet-metal walls of these ports, on the other hand, are not subject to much pressure, because when they are performing their exhaust function the 9 burned gases are released and are merely deflected by the pockets to the exhaust outlet at one side, in addition to which it is of no moment if the pocket walls should become slightly warped, since they form no part of the blanking and bearing surface of the 10 valve.

While I have described this part of the invention in connection with my prior type of valve, wherein it is especially effective, it will be perceived that it is not necessarily 11 limited thereto, since it may be applied to other forms of rotary valve controlling the exhaust of an internal combustion engine and having internal means for cooling the 12 rotary valve member.

As a further part of the invention I provide one, or preferably a number of continuous longitudinal channels 90 in the face of the bore of the casing, next to the surface of the rotating valve member, these channels 1 being constantly open to the supply of fresh gases and being located between the top of the continuous, or virtually continuous, intake port 70 and the top of the casing bore. (By the top of the bore it is to be understood that I mean the part diametrically opposite the cylinder ports 4.) In this location, the channels, at different portions along their lengths, are connected at different times with the intake opening and manifold 70, 11, by the valve pockets 8 or 8^a, as the valve revolves. The effect of this is to cause a flow of fuel gases, induced by the suction of the engine, through the channels into the intake manifold at shifting points along the length. 1 This flow is direct as compared with the circuitous route through the interior of the valve member, supplements the capacity of this passage, diminishes the tendency of one cylinder or set of cylinders to receive charges 1 more heated than the others, very materially increases the efficiency of lubrication and sealing of the valve surfaces by the lubricant carried by the fuel, and makes it possible to reduce the width of the longitudinally ex- 1

tending gap 70 in the stationary bearing surface of the valve casing.

What I claim as new is:

1. A rotary combined intake and exhaust valve for internal combustion engines, of the kind comprising a rotary valve member turning in the bore of a casing and having a lateral port pocket to connect a cylinder port alternately with intake and exhaust openings on either hand, the valve member being further provided with a longitudinal internal passage connecting circuitously with said intake opening and forming part of the intake of the engine, so that part or 15 all of the fresh gases flow therein to the intake opening and thence by way of the port pocket to the cylinder, characterized by the wall of the valve member being relatively massive and containing a cavity which is 20 occupied by a very thin dished wall forming the pocket, said thin pocket wall connecting with the massive wall of the valve member near the outer surface of the latter so that it is accessible on its inner surface to the 25 cool gases substantially to its edges at the outer region of the valve body.

2. A rotary valve controlling the exhaust of an internal combustion engine, of the kind comprising a rotary valve member 30 turning in the bore of a casing and having a lateral port pocket in its side to connect a cylinder port with an exhaust port at one side, the valve member being further provided with a longitudinal internal passage 35 through which cooling fluid is passed, characterized by the valve member having a massive wall containing an opening extending through it to the center at the pocket region, and by a sheet-metal pocket lying in 40 and closing said opening in the massive wall and exposed at its inner surface to the cooling medium in the central passage.

3. A rotary combined intake and exhaust valve for internal combustion engines, of the kind comprising a rotary valve member turning in the bore of a casing and having a lateral port pocket to connect a cylinder port alternately with intake and exhaust openings on either hand, the valve member 50 being further provided with a longitudinal internal passage connecting circuitously with said intake opening and forming part

of the intake of the engine, so that part or all of the fresh gases flow therein to the intake opening and thence by way of the port 55 pocket to the cylinder, characterized by the relatively massive wall of the valve member having an opening extending through to the center at the pocket region, and by a dished sheet-metal pocket inserted in said opening 60 joined to the body of the valve member at the edges and elsewhere free.

4. A rotary combined intake and exhaust valve for multicylinder internal combustion engines, of the kind comprising a casing 65 having a bore, intake and exhaust manifold openings on either hand and intermediate cylinder ports, and a rotary valve member turning in said bore and having port pockets in its sides to connect said cylinder ports 70 alternately with the intake and exhaust openings, characterized by the face of the valve seat bore being provided with one or more longitudinal channels constantly open to the supply of fresh gases and extending 75 substantially full length of the valve between the top of the intake opening and the top of the bore, in position to be connected with the intake opening by the valve pockets 80 at different points as the valve revolves.

5. A rotary combined intake and exhaust valve for multicylinder internal combustion engines, of the kind comprising a casing having a bore, intake and exhaust manifold openings on either hand and intermediate 85 cylinder ports, and a rotary valve member turning in said bore and having port pockets in its sides to connect said cylinder ports alternately with the intake and exhaust openings, the valve member being further 90 provided with a longitudinal internal passage affording an indirect path from the source of supply of fresh gases to the intake manifold, characterized by the casing having one or more longitudinal channels in the face 95 of its bore forming a supplementary direct route for fresh gases, said channels being constantly open to the supply and located between the top of the intake opening and the top of the bore, in position to be connected with the intake manifold opening by 100 the valve pockets as the valve revolves.

EUGENE M. BOURNONVILLE.
